DISPLAY PACKAGING CONTAINER

John Donald Bostrom, Niles, Ill., assignor to Poster Packaging, Inc., Chicago, Ill., a corporation of Delaware

Filed Feb. 1, 1961, Ser. No. 63,790

Term of patent 14 years

(Cl. D58—11)

FIG. 1

FIG. 2

FIG. 3

FIG. 4

FIG. 1 is a perspective view of a display packaging container embodying my new design;

FIG. 2 is a top plan view thereof;

FIG. 3 is a bottom plan view thereof; and

FIG. 4 is a sectional view taken along the line 4—4 of FIG. 2.

The bottom for the container shown in broken lines is plain.

The broken line showing is for the purpose of illustration only.

I claim:

The ornamental design for display packaging container, as shown and described.
